CLAIM

The ornamental design for an electric shaver, as shown and described.

DESCRIPTION

FIG. 1 is a front, right and top perspective view of an electric shaver, showing my new design;
FIG. 2 is a rear, left and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof;
FIG. 9 is an exploded view of the electric shaver;
FIG. 10 is an enlarged view of the portion of the electric shaver shown within the area designated as **10** in FIG. 1; and,
FIG. 11 is an enlarged view of the portion of the electric shaver shown within the area designated as **10** in FIG. 9. The broken lines shown in the drawings illustrate portions of the electric shaver that form no part of the claimed design. The dot-dash broken lines encircling portions of the electric shaver in FIGS. 1 and 9 and illustrated in enlarged views in FIGS. 10 and 11 form no part of the claimed design.
